UNITED STATES PATENT OFFICE.

OTTO A. HOKANSON, OF WOODSTOCK, ILLINOIS, ASSIGNOR TO WOODSTOCK TYPE-WRITER COMPANY, OF WOODSTOCK, ILLINOIS, A CORPORATION OF ILLINOIS.

TYPEWRITER.

Application filed March 17, 1924. Serial No. 699,727.

This invention relates to typewriting machines, and more especially to machines of this nature provided with a power driving device.

5 The invention has for its object the provision of a typewriting machine which shall be controlled by a keyboard in the usual manner, but in which the work of moving keys and other parts shall be performed by power actuated mechanism.

Another object of the invention is to provide a power actuated typewriter which shall be of improved construction and operation.

15 The invention is exemplified in the combination and arrangement of parts shown in the accompanying drawings and described in the following specification, and as more particularly pointed out in the appended claims.

20 In the drawings—

Fig. 1 is a fragmentary vertical sectional view of a typewriting machine showing one embodiment of the present invention;

25 Fig. 2 is a view similar to Fig. 1, but showing mounting for the platen;

Fig. 3 is a fragmentary bottom plan view with parts in section showing the mechanism illustrated in Fig. 2;

30 Fig. 4 is a fragmentary top plan view with parts in section showing the motor and its associated parts;

Fig. 5 is a fragmentary front elevation of the adjusting lever for the platen; and

35 Fig. 6 is a vertical section substantially on line 6—6 of Fig. 2.

It is well known that prolonged operation of a typewriting machine produces a fatiguing strain on the operator because of the force with which the keys must be struck in order to produce the proper impression from the type. This is especially true of machines having a form of action in which the type members make their impression at about the time at which they reach the limit of a prescribed range of movement, and especially in machines of this type provided with moving parts having considerable weight to impart the necessary momentum to produce a clear impression at the extremities of the movements of the type carrying members.

In the present invention this difficulty is avoided and a more speedy action is obtained by providing power mechanism for producing the movement of the operating

parts, it being necessary to depress the keys only a sufficient amount to control the power mechanism.

Referring more particularly to the drawing, the numeral 10 designates the frame 60 of a typewriting machine having a plurality of horizontally sliding type carrying members 11 which travel in guides in the upper plate 12 of the frame, the guides all converging toward a common center adjacent the front face of the platen 13. The type carrying members 11 are moved by a pair of toggle links 14 and 15 which are pivoted to one another at 16, one of the links being pivoted to the member 11 at 17, while 70 the other link is mounted on a stationary pivot 18 on the arm 19. The arm 19 is secured to the portion 20 of the main frame by means of an integral bar 21 held by screws 22 and 23. The arm 19 is bifurcated, the 75 forward portion supporting a pivot 24 having a cam 25 journaled thereon. The rear portion of the arm 19 carries a pivot 26 on which a bell-crank 27 is supported. The upper arm 28 of the bell-crank 27 is pivoted 80 at 29 to a link 30 which in turn is pivoted at 31 to a forwardly projecting bar 32 on the toggle link 15. The link 30 is extended rearwardly and provided with a weighted end 33 to impart momentum to the moving parts 85 when the machine is operated. The lower arm 34 of the bell-crank 27 underlies the cam face of the cam 25. A tail piece 35 is secured to the bell-crank 27 in position to strike a rubber cushion 36 at the limit of 90 the movement of the operating parts.

A spring 37 normally rests upon the arm 34 and holds the operating parts in their retracted position in which the weighted portion of the link 15 rests upon a cushion 95 38. The arm 34 is provided with a downwardly extending tappet 39 which engages a universal bar 40. A link 41 is pivotally connected at 42 to the cam 25 and has its lower end pivoted at 43 to a pivoted member 100 44 mounted on the rod 45 extending transversely of the machine. An actuator 46 is pivotally connected at 47 to the member 44 and is provided at its rear end with a hook 48 for engaging a ratchet cylinder 49. The 105 cylinder 49 has its opposite ends journaled in the side of the machine and is provided at one end, as shown in Fig. 4, with gears 50 connecting the cylinder to a motor 51 by means of shaft 52 and worm gear 53. The 110

motor 51 is mounted, in the embodiment shown, at the rear of the frame 10. A spring 54 normally holds the actuator 46 out of engagement with the ratchet cylinder 49, 5 the upward movement of the actuator being limited by a bar 55 extending transversely of the machine in position to engage the various actuators 46. The rear end of the actuator 46 is extended to provide a cam 10 face 57 for engaging a roller 58 extending transversely of the machine and supported by a pair of arms 59 one at each side of the machine pivoted at 60 to the frame. Each 15 of the arms 59 has a jaw member 61 which engages an eccentric cam 62 on a shaft 63 journaled in the side frames of the machine. The shaft 63 as shown in Fig. 4 is provided with a hand lever 64 which carries a spring pressed finger piece 65 having a pin 20 removably engaging openings in a quadrant 66 to retain the shaft in various positions of adjustment. It will be apparent that as the shaft 63 is rotated the arms 59 and consequently the roller 58 will be adjusted 25 toward or away from the projections 57 of the actuator 46.

Each of the actuators 46 is provided with a laterally extending lug 67 which engages a hook 68 formed on the upper end of a connector 69 pivoted at 70 on the key lever 71. The key levers 71 are pivoted at 72 near the rear of the machine and are held in their uppermost positions by springs 73 in a well known manner.

35 Each of the connectors 69 is provided with a slot 74 to provide limited vertical movement relative to the key lever 71 and a stop 75 engages a projection 76 on the key lever to limit the forward pivotal movement 40 of the connector.

Any suitable switching mechanism may be used for starting and stopping the motor 51, and when the motor is operating the ratchet cylinder 49 will continuously rotate 45 in a clockwise direction as viewed in Fig. 1.

If now any one of the key levers 71 is depressed the hook 48 will engage one of the teeth of the ratchet cylinder so that the actuator will be moved rearwardly for a 50 short distance. The movement of the actuator in its depressed position will free the contact member 67 and 68 so that the actuator will be free to return to its uppermost position under the influence of spring 55 54. The cam face 57 acting on the roller 58 will positively disengage the hook 48 from the tooth of the ratchet drive cylinder 49 so that the actuator will be positively freed at a definite time, the exact time of release being determined by the adjustment of the roller 58 by the cam 62. The impulse thus given to the actuator 46 will be transmitted to the cam 25 through the link 41 and from the cam 25 to the bell-crank 27 60 and link 30 to the toggle arms 14 and 15

and to the type support 11. This will start the type support in its sliding movement toward the platen 13, but before it reaches the limit of its movement as determined by the toggle links 14 and 15 and the stop 36 the 70 actuator will be released from the power drive so that the stroke will be completed by the momentum of the parts including the weighted member 33.

It will be seen that the power drive is especially adapted to a type bar action of this kind because of the fact that greater momentum can be imparted to the moving parts during a short range of movement than can be done by manual operation. If 80 the operator should hold the key lever 71 depressed for a sufficient length of time to permit the actuator 46 to return to normal position prior to the release of the key lever the pivoted hook portion 68, together with the lower bevelled edge of the projection 67 will cause the connector 69 to snap into place above the projection 67 whenever the key lever 71 is released.

Because of the radial position of the type 90 bar supports 11 the position of the pivots 24 may vary fore and aft of the machine. It will be desirable to locate the transverse bar 25 about midway between the extreme 95 fore and aft positions of the pivots 42 so that the angularity of the link 41 will not vary too greatly. The position of the pivots 43 on the arm 44 may be varied to compensate for any variation of the type bar action due to the angularity of the links 41. It 100 will be understood that the actuators 46 are arranged in parallel relation so that they travel at right angles to the cylinder 49. This will bring the pivots 42 and 43 slightly out of parallel relation for the type actions 105 at the sides of the machine, but this lack of parallelism may be compensated for by imparting a slight twist to the links 41.

It will be understood that the adjustment 110 of the roller 58 will change the period of contact between hook 48 and the teeth of the roller so as to impart varying degrees of momentum to the type action, and thus give varying force to the impression of the type 115 upon the paper. Since the type supports are moved to the limit of their path of travel at each operation and are not arrested by the platen, it is desirable to adjust the platen toward and from the impression point so as to insure the proper contact of the type upon the paper. In order to secure 120 this adjustment of the platen a slide 77 is mounted in ways formed in the top plate 12 and is provided with a rearwardly projecting bracket 78 having a plate 79 projecting laterally from each side of the bracket. Arms 80 are adjustably mounted by means of pivoted blocks 81 and links 82 at each side of the bracket 78. These arms 125 support a track 83 on which the platen car- 130

riage 84 is mounted for lateral movement. The travel of the carriage is controlled by a rack 85 and an escapement pinion 86 operated in any well known manner. A link 5 87 is secured to the front of the slide 77 and is threaded into a sleeve 88 at its forward end. The sleeve 88 is journaled to rotate in the front plate 89 and has an arm 90 adjustably secured thereto by a screw 91.

10 A spring 92 is interposed between the rear face of the plate 89 and a collar 93 fixed to the link 87.

Rotation of the arm 90 draws the link 87 forwardly by means of its threaded connection with the front end of the link. 15 Movement of the arm in the opposite direction releases the link 87 so that it is moved rearwardly by the spring 92. By this means the platen 13 may be accurately adjusted 20 toward and away from the contact point with the type. A graduated segment 94 may be provided for indicating the position of the arm 90.

I claim:

25 1. The combination with a sliding type carrier, of a vertically movable member for actuating said type carrier, a power drive, a horizontally movable actuator arranged to engage said power drive, a pivoted member 30 connected with said actuator, and a link con-

nnecting said pivoted member and said vertically movable member.

2. The combination with a horizontally sliding type carrier, a toggle for imparting movement to said type carrier and for arresting said type carrier at the limit of its range of movement, a platen adjustable toward and away from said type carrier, operative mechanism for said toggle, cushioning means for arresting said operative mechanism at the limits of the movement thereof in either direction, a spring for retracting said type carrier, a motor actuated drive, an actuator arranged to engage said drive, means for operatively connecting said actuator with said toggle operating mechanism, a key lever, a connector arranged to engage said actuator to move said actuator into operative relation with said drive and disengageably therefrom by the movement imparted to said actuator by said drive, and an adjustable device for disconnecting said actuator from said drive during the movement imparted by said actuator to said type carrier. 55

In testimony whereof I have signed my name to this specification on this 15th day of March, A. D. 1924.

OTTO A. HOKANSON.
